UNITED STATES PATENT OFFICE.

CHARLES M. GODDARD AND WILLIAM E. POWELL, OF DENVER, COLORADO.

DRILL BIT.

Application filed June 3, 1922. Serial No. 565,714.

To all whom it may concern:

Be it known that we, CHARLES M. GODDARD and WILLIAM E. POWELL, citizens of the United States, residing at the city and county of Denver and State of Colorado, have invented certain new and useful Improvements in Drill Bits; and we do declare the following to be a full, clear, and exact description of the invention, such as will 10 enable others skilled in the art to which it appertains to make and use the same, reference being had to the accompanying drawings, and to the characters of reference marked thereon, which form a part of this 15 specification.

This invention relates to drills and has special reference to a drill bit adapted for use in coal mining.

In mining coal it is necessary to bore 20 holes of considerable size into the coal in order to insert the explosives, and sometimes for other purposes. As the drills are operated by electricity or by compressed air, it is essential that they be so designed that 25 they may be turned with a minimum amount of power so that the motor apparatus can be kept down to a reasonable size and weight.

It is the object of this invention to produce 30 a drill that shall be so constructed that it will be capable of great speed and can be turned with a much smaller amount of power than drills of ordinary construction and of the same effective diameter.

The above and other objects that will be 35 readily apparent as the description proceeds are attained by means of a construction which we will now describe in detail, reference being had for this purpose to the accompanying drawings in which—

Fig. 1 is a side elevation of our drill bit;

Fig. 2 is a vertical section thereof taken on line 2—2, Fig. 3;

Fig. 3 is an elevation looking in the direction of the arrow 3 in Fig. 1;

Fig. 4 is a section taken on line 4—4, Fig. 1; and

Fig. 5 is a section taken on line 5—5, Fig. 3.

The same reference numbers will be used 50 to designate the same parts throughout the several views.

Numerical 1 represents the main body portion of our bit which, broadly speaking, is 55 a rectangular piece of steel having two up-

per end corners removed by a diagonal cut. The lower end—and by the terms upper and lower we have reference to the position in which the bit is shown on the drawing—has a rectangular recess 2 which is adapted 60 to receive a correspondingly shaped shank member 3 (Fig. 1) by means of which the bit is rotated. The upper end of the bit has a hole 4 which may have a standard drill taper as shown, or which may be of any 65 other suitable cross section. Within hole 4 we place a drill 5, in the manner clearly shown in the drawing. The opposite narrow sides are each channelled as indicated by numerals 6 and 7, and within each channel we place a cutter 8 which is held in place by a screw 9. These cutters are provided with inclined ends 10 and have their front sides cut away in the manner indicated by numeral 11, so as to form a 70 cutting tooth 12. The upper end of the drill bit between the drill 5 and the cutters 8 is beveled or inclined as indicated by numeral 13, and has secured thereto steel cutters 14 which are held in place 75 by means of screws 15. The upper end of each cutter 14 is beveled so as to form a cutting edge 16, the purpose of which will become readily apparent as the description 80 proceeds. On each of the wide or flat sides we provide an elongated ridge 17 which extends diagonally across the sides in the manner shown in Fig. 1. The purpose of the ridge 17 is to move the powdered coal 85 downwardly or away from the cutter towards the shank member 3.

The operation of our bit or cutter is as follows: The shank 3 is rotated in the proper direction and drill 5 then cuts into the coal. When the drill 5 has entered a 90 short distance, the cutters 8 will strike the surface of the coal and begin to cut a circular groove therein; this leaves a ring of coal between drill 5 and cutters 8. As the drill proceeds the cutters 14 will engage 95 the outer end of the coal ring and cut this away at the same speed at which the drill enters into the coal. In the manner just described, the drill will cut a clean hole at a comparatively fast speed and with the 100 expenditure of a minimum amount of power. The drill 5 may be readily removed and sharpened or replaced, and the cutters 8 are made double ended so that when they become dull they may be reversed, and 105 110

when both of the cutting edges become dull, they may be reground.

In the above description we have referred to the portion 3 merely as a shank, but we want it understood that this shank is a portion of the twisted auger stem which is usually employed in drills of this nature, as without the auger stem it would, of course, be impossible to operate the drill in holes of any considerable depth, as the powdered coal would remain therein and prevent the stem from freely rotating.

Although we have laid particular stress on the fact that this drill bit may be operated with a smaller expenditure of power than ordinarily the case for any drill of this size, it is of course understood that this bit may be operated by hand as well as by air or electricity, and the ease with which it can be operated is just as important in the latter case as in the former.

It is apparent from the above that we have devised a drill bit that is especially well adapted for use in drilling coal, and which is so designed that it can be operated

at great speed and with a minimum expenditure of power.

Having now described our invention, what we claim is—

A device for drilling coal comprising a body member of substantially rectangular cross-section, a channel in each narrow side and extending parallel to the central axis of the member, a removable cutter in each channel, a central socket in said body member, said socket being located midway between the channels and concentric with the central axis of the body member, a drill in said socket, the spaces on each side of the drill and the removable cutter being inclined at an angle to the side surface of the body member and also inclined with respect to the edge surface thereof, and a removable cutter secured to each inclined surface and adapted to cut the coal between the drill and the outer cutter.

In testimony whereof we affix signatures.

CHARLES M. GODDARD.
WILLIAM E. POWELL.
